DECALCOMANIA

William Hepp, Cincinnati, Ohio, assignor to The Palm Bros. Decalcomania Company, Cincinnati, Ohio, a corporation of Ohio

Application August 17, 1931, Serial No. 557,488

7 Claims. (Cl. 41—33)

My invention relates to decalcomanias.

It is the object of my invention to provide a decalcomania that is easily detached from its temporary supporting back and applied to a permanent supporting surface; and which is impervious to the action of the elements and cleansing materials which may be applied to it from time to time to clean the surface of its permanent support.

10 It is a further object to provide a decalcomania in which the ink impressions of the design or the background of the design, or both, are provided with a supporting blanket of opaque material, such as white ink, which not only enhances the 15 color values of the design above this white opaque sheet, but which enables this sheet to be applied to surfaces having other decalcomanias on it or other designs so that the old designs or old decalcomanias will not show through the new one of 20 my invention.

It is a further object to provide such a combination with a lacquer coating over the face of the design and over the back of the design with the ink impressions and the white opaque backing sheet between the two lacquer coats.

25 It is a further object to provide means of arranging designs of different kinds, colors and materials so that the printing of one will not disturb the printing of the other or the results of 30 the printing of the other and the two designs will be maintained in registration while, at the same time, having a common white backing coat for performing the foregoing results for both of the 35 designs; and, in particular, it is my object to provide means of printing bronze, gold, silver and other designs which are easily disturbed by subsequent printings; of locating said designs of bronze, silver, etc., so that the bronze, silver, etc. 40 will not be hidden by subsequent designs, and then covering such designs with a lacquer, and thereafter proceeding with the formation of the decalcomania as heretofore set forth.

45 It is a further object of my invention to provide means of including a color design between layers of lacquer with the white backing being arranged only in the design as formed by the color impressions, thereby providing a design which, when transferred, has all the advantages of the white backing behind the color impressions, but 50 the design elements are held together by the superimposed engaging films of lacquer.

Referring to the drawing:

Figure 1 is a diagrammatic view broken away in successive layers to show the complete white 55 coat over the color impressions and the area be-

tween the color impressions located between superimposed layers of lacquer;

Figure 2 is a similar view showing the arrangement of the bronze, silver, etc. design separately printed and protected by its coating of lacquer 60 and thereafter the arrangement of Figure 1 for the rest of the decalcomania is effected without disturbing the design in delicate bronze, silver, etc.:

Figure 3 is a similar view showing the color 65 impression of the design having the white coating backing but the elements of the design retained together as a composite design with superimposed films of embracing lacquer.

Referring to the drawing in detail, 1 is the 70 paper backing that is used as the temporary support for the decalcomania. This paper is coated with an adhesive 2 upon which is mounted a nitro-cellulose lacquer coat 3. This lacquer coat has printed thereon the design consisting of the 75 ink impressions 4 over which is placed a sheet comprising a series of ink impressions of white ink designated 5. This white ink opaque sheet is of sufficient density to not only bring out the 80 design 4 and the values of the colors in that design, but also it is of such thickness and opacity as to prevent any design beneath it after transfer from being seen through the decalcomania now under consideration. Mounted over this white 85 layer 5 is a nitro-cellulose lacquer layer 6 and on the back of the lacquer layer 6 is an adhesive layer 7 which is utilized for attaching the decalcomania to its permanent supporting surface.

It will be understood that the adhesive 2 is of 90 the usual character that is water soluble enabling the decalcomania to be detached from the paper 1 or the paper 1 detached from the decalcomania.

In Figure 2 I have shown printed upon the 95 adhesive 2 a varnish coat 8 printed in the design that is desired for a subsequent bronze, gold, silver, or other printing, where the material being printed is of such delicate character that subsequent printings will make it difficult, if not impossible, to prevent injury to the bronze, 100 etc. design. If desired, a lacquer coat 2a may be printed or laid on the soluble adhesive 2 prior to printing the varnish design 8.

Again, the material used for the printing of 105 the bronze, silver, gold etc. design will adhere to the varnish. Consequently, after I have printed the design 8 in varnish, I again print it in the desired bronze, silver, gold, etc., as at 9. Thereupon, I coat the entire surface with lacquer 3 110

and continue as heretofore described in connection with Figure 1.

In Figure 3 I provide another form of the general scheme heretofore described in that upon the paper 1 and adhesive 2 and the lacquer coat 3 I print a design in color impressions 4 and then upon the color impressions 4 in the same design I print in white ink as at 10 so that the specific designed is backed up with the opaque white ink 10 coats, of which there may be any desired number to render the ink impressions 4 opaque and to bring out their color values and to give body to the designs and to retain the ink impressions in registration as there may be a plurality of 15 colors employed in making up a single design. I then place the lacquer coat 6 over the entire surface and lastly place the adhesive 7 on the surface of what will become the back of the decalcomania when it is mounted upon its permanent 20 supporting surface. Thereupon, upon transfer, the designs 4 and 10 will be held in predetermined relationship between the films of transparent lacquer 3 and 6 in their predetermined relationship to spell the words or to form any 25 designs that may be desired.

It will be understood that my drawing is diagrammatic and is for the purpose of illustration only and is greatly exaggerated in order to illustrate the principles involved.

30 It will be further understood that when I refer to white opaque ink coats, to lacquers, to color coats and to bronze, gold, silver, etc., I comprehend within my invention such modifications of materials and other details of executing the invention as may be within the range of those skilled in the art or necessary to adapt my invention to changing conditions of industry and commerce.

35 It will be further understood that I desire to comprehend within my invention such modifications as may be necessary to adapt it to varying conditions and uses.

Having thus fully described my invention, what I claim as new and desire to secure by Letters 40 Patent, is:

45 1. In combination, a temporary supporting medium, a soluble adhesive mounted thereon, a lacquer coat, an ink impression design printed thereon, an opaque sheet covering said design and lacquer coat, a second lacquer coat and a coat of attaching adhesive.

50 2. In combination in a decalcomania of a lacquer coating, a design consisting of ink impressions, an opaque backing of white ink for said design following the configurations thereof, a second lacquer coating printed coextensive with the first lacquer coating and extending beyond said design and opaque backing therefor, a temporary support and water soluble adhesive for 55 supporting said decalcomania on one of said

lacquer coatings, and a permanently attached adhesive on the other of said lacquer coatings.

5 3. In combination in a decalcomania of a temporary support, a soluble adhesive thereon, a design printed in varnish, a varnish adhesive material printed thereon adapted to adhere to said varnish, a lacquer coat covering said design and said adhesive support, a second design printed in ink, a lacquer coat, and means of attaching said decalcomania to a permanent supporting 10 surface.

10 4. In combination in a decalcomania of a temporary support, a soluble adhesive thereon coextensive therewith, a design printed on a portion thereof in varnish, varnish adhering material superimposed on said design, a lacquer coat coextensive with said adhesive and said support covering said varnish and varnish adhering material in the design, a second design printed on said lacquer with ink, an opaque backing coextensive with the outlines of said sheet, a second coating of lacquer, and a permanently attached coating of adhesive on the second coat of lacquer.

15 5. In combination in a decalcomania of a temporary support, a soluble adhesive thereon coextensive therewith, a design printed on a portion thereof in varnish, varnish adhering material superimposed on said design, a lacquer coat coextensive with said adhesive and said support covering said varnish and varnish adhering material in the design, a second design printed on said lacquer with ink, an opaque backing coextensive with the outlines of said sheet, a second coating of lacquer, and a permanently attached coating of adhesive on the second coat of lacquer, 20 said successive designs being so arranged that they are in offset relationship whereby both of them may be viewed when the decalcomania is detached from its temporary support and soluble adhesive and permanently mounted on a permanent support by the permanently attached adhesive.

25 6. In combination in a decalcomania of a lacquer coat, a design printed in a gum material in tacky condition, a layer of gum adhering 120 bronze printed thereon, a second coat of lacquer, an ink impression design printed on the second coat of lacquer, a third coat of lacquer, and means of attaching the decalcomania so formed to a permanent surface.

30 7. In combination, a coat of lacquer, a design printed in varnish, bronze imprinted on said varnish design to which it will adhere without adhering to the lacquer, a second coat of lacquer, an ink impression design printed on the second 130 coat of lacquer, an opaque sheet of white ink adapted to cover the second coat of lacquer and the ink impression design, a third coat of lacquer, and a permanently attached adhesive.
